TRAFFIC LIGHT SIGNAL

Douglas B. Hughes, 6501 Bruton Road,
Montreal, Quebec, Canada

Filed July 9, 1962, Ser. No. 70,849

Term of patent 14 years

Claims priority, application Canada Apr. 6, 1962

(Cl. D72—1)

FIGURE 1 is a plan view of a traffic light signal embodying my new design,

FIGURE 2 is a front elevation of the traffic light signal,

FIGURE 3 is a rear elevation of the traffic light signal, and

FIGURE 4 is an end view of the traffic light signal.

The support arm is broken away in the views to indicate indeterminate length.

I claim:

The ornamental design for a traffic light signal, as shown and described.
